[57] CLAIM

The ornamental design for a room air conditioner front enclosure, as shown and described.

DESCRIPTION

FIG. 1 is a front elevational view of a room air conditioner front enclosure showing my new design;

FIG. 2 is a right side elevational view thereof, the left side being a mirror image;

FIG. 3 is a top plan view thereof, the bottom being identical in appearance; and

FIG. 4 is a partial enlarged vertical cross-sectional view thereof, taken along line 4—4 of FIG. 1.
